UNITED STATES PATENT OFFICE.

DAVID BARKER, OF STEUBENVILLE, OHIO, ASSIGNOR TO CHARLES G. SUMMERS, OF BALTIMORE, MARYLAND.

DESIGN FOR A PICKLE, PRESERVE, OR SIMILAR VESSEL.

SPECIFICATION forming part of Design No. 12,887, dated April 18, 1882.

Application filed February 15, 1882. Term of patent 3½ years.

To all whom it may concern:

Be it known that I, DAVID BARKER, a citizen of the United States, residing at Steubenville, in the county of Jefferson and State of Ohio, have invented and produced a new and original Design for a Pickle, Preserve, or other Similar Vessel, of which the following is a specification, reference being had to the accompanying drawing, forming part thereof, which 5 represents a side elevation of my newly-designed vessel.

The leading features of my design consist of a glass vessel having a cylindrical body ornamented by a series of angular horizontal ribs 15 extending partially around the same, and a series of vertical angular ribs crossing said ribs at right angles, and a medallion at each side of the body of the vessel having an ornamental border with the figure of a swan at the center, the body being provided with a series of 20 annular beads at the top and bottom, and with a beaded base, ornamental handles, and a dome-shaped horizontally-beaded top, surmounted by the figure of a swan.

25 The letter A indicates the cylindrical body of the vessel, which is provided with a series of parallel horizontal ribs, B, extending partially around it, and with a series of vertical ribs, C, crossing the horizontal ribs at right angles.

30 The letter D indicates a medallion, one on each side of the vessel, the said medallion being surrounded by an ornamental border in raised lines E F. At the center of each medallion is the figure of a swan, (indicated by the letter G.) The top and bottom of the vessel

are provided with the beads H I K, and the body rests upon a beaded base, I.

M indicates a beaded dome-shaped cover surmounted by the figure of a swan, as indicated by the letter N.

The letter P indicates two ornamental handles. These are located on opposite sides of the body, their bases R forming the starting-point of the horizontal angular ribs, the vertical angular beads commencing at some distance from each side of the bases, so as to leave a series of short horizontal grooves, S, immediately adjoining the bases. The handles are formed with vertical standards T, which 45 at each end are enlarged and provided with 50 star-shaped ornaments U, as shown.

I claim—

1. The design for a pickle, preserve, or other vessel herein shown and described, consisting 55 of the body A, having intersecting horizontal and vertical ribs, a beaded top and bottom, a beaded base and cover, medallions at each side bearing the figure of a swan, a beaded top surmounted by the figure of a swan, and ornamental handles, substantially as specified.

2. The design for a preserve, pickle, or other vessel, consisting of cylindrical body having intersecting ribs, and a medallion at each side bearing the figure of a swan, beaded upper and 65 lower portions, a beaded base, and ornamental handles at opposite sides, substantially as specified.

DAVID BARKER.
